UNITED STATES PATENT OFFICE.

WALTER O. McDANIEL, OF INDIANAPOLIS, INDIANA, ASSIGNOR TO THE H-K TOY & NOVELTY CO., OF INDIANAPOLIS, INDIANA, A CORPORATION OF INDIANA.

TOY MOTOR-VEHICLE.

1,375,713.

Specification of Letters Patent. Patented Apr. 26, 1921.

Application filed June 15, 1918. Serial No. 240,256.

To all whom it may concern:

Be it known that I, WALTER O. McDANIEL, a citizen of the United States, residing at Indianapolis, in the county of Marion and State of Indiana, have invented a new and useful Improvement in Toy Motor-Vehicles, of which the following is a specification, reference being had to the accompanying drawings, and to the letters and figures of reference marked thereon.

This invention relates to a toy that is designed to be moved either by pulling it or pushing it, and has reference more particularly to an imitation of a motor vehicle that is adapted to have either a truck body or such style body as may be desired; the invention having reference also to steering apparatus for the toy.

An object of the invention is to provide an interesting and instructive toy for small children which shall be of simple and inexpensive construction and not be liable to serious injury with rough usage.

Another object is to provide an amusing and harmless toy which shall be so constructed as to represent or have the appearance of a real motor vehicle, and which may be principally constructed inexpensively of small pieces of wood and so that it shall be adapted to be inexpensively painted or decorated to give the toy a realistic appearance.

With the above-mentioned and other objects in view, the invention consists in a novel construction in toy vehicles and more particularly in novel steering apparatus adapted to be set to guide the vehicle in a definite course; and, the invention consists also further in the novel parts and combinations and arrangements of parts as herein-after particularly described and further defined in the accompanying claims.

Referring to the drawings,—Figure 1 is a side elevation of the toy constructed substantially in accordance with the invention; Fig. 2 is a front elevation of the toy, Fig. 3 is a bottom plan of the toy; Fig. 4 is a fragmentary section approximately on the line IV—IV in Fig. 1; Fig. 5 is a fragmentary longitudinal vertical section approximately on the line V—V in Fig. 3; and, Fig. 6 is a perspective view of a number of connected parts of the steering apparatus.

Similar reference characters in the different figures of the drawings indicate like

parts or features of construction referred to in detail.

The toy has four wheels 1, 2, 3, 4, and as preferably constructed each wheel is composed of a single piece of wood and has a hub 5 in which is a journal bore 6, a thin web 7 extending from the hub, and a rim 8 on the web formed to imitate a pneumatic tire in appearance, being approximately cylindrical in cross section. The toy has a front axle bar 9 and a relatively longer wooden rear axle 10, each being approximately square in cross section. Two frame bars 11 and 12 are rigidly secured upon the axle bar 9 and extend divergently each to the other to the top of the rear axle to which they are rigidly secured. A filling piece 13 is secured upon the axle bar between the frame bars. The axle bar 9 has slots 14 and 15 extending inward from the two opposite ends respectively of the bar and are normally positioned horizontally. Two stub axle bodies 16 and 17 are provided which are approximately square in cross section and have pivot ears 18 and 19 on one end thereof respectively that are fitted respectively into the slots 14 and 15 and connected with the axle bar by means of vertical pivot pins 20 and 21 respectively. The opposite end of each stub axle body has a socket 22 therein in which an axle journal 23 is rigidly secured, the outer end of the journal having a collar 24 integral thereon. The axle journal extends through the bore 6 of the wheel, the wheel having a side bearing against the end of the axle body and being retained in place by the collar. The remaining wheels are similarly mounted on the axle portions.

The frame of the vehicle has a floor board 25 which is secured upon the frame bars 11 and 12 and the filling piece 13. A block 26 composed of wood is suitably shaped to represent one of the well known styles of engine hood as to external contour and is secured upon the floor board 25, the forward end of the block being painted in imitation of a radiator. A dash board 27 is secured to the rear end of the block, and a wooden block 28 designed to represent a seat is secured upon the floor board 25 rearward of the dash board, a seat back 29 being secured to the rear side of the seat block. A suitable vehicle body 30 is mounted upon the vehicle frame back of the seat back 29. The forward portion of the vehicle frame has buffer

blocks 31 and 32 thereon which preferably are composed of extensions of the frame bars 11 and 12 respectively.

A novel steering shaft 33 is provided which has a crank arm 34 integral with its lower end, the arm being at an obtuse angle relatively to the shaft and having an eye 35 on its end. The shaft is arranged at an inclination in a guide bore 36 made in the block 23 at an inclination, the shaft extending through a guide hole 37 made in the dash board 27 and also through an aperture 38 in the floor board 25. A tube 39 is arranged on the shaft 33 and has a beveled end seated against the rear side of the dash board 27. A steering wheel 40 is suitably secured to the upper portion of the shaft 33 and is supported upon the upper end of the tube or casing 39 to support the steering shaft. One of the stub axle bodies, 17, is provided with an eye 41 on its rear side for controlling the stub axles. A connecting link 42 is provided which has an eye 43 on one end that is connected with the eye 41, and another eye 44 on its opposite end that is connected with the eye 35. The eyes on the link are disposed at right angles each relatively to the other to afford substantially pivotal connections with the eyes 35 and 41. The forward sides of the stub axle bodies 16 and 17 are suitably provided with coupler eyes 45 and 46 respectively, a coupler rod 47 being provided that has pivots 48 and 49 integral thereon which are arranged in the eyes 45 and 46 respectively, the eyes supporting the coupler rod.

A pair of painted wooden blocks 50 and 51 made in imitation of head lights are suitably mounted upon the buffer blocks 31 and 32 respectively. The vehicle may be variously painted and ornamented, and different colors may be used to make the toy attractive.

In practical use the vehicle is rolled upon the ground or upon the floor, and the steering wheel 40 may be turned so as to swing the arm 34 for guiding the forward wheels. There will be slight frictional resistance of the steering shaft in its guides, so that when the steering wheel 40 is set either to cause the vehicle to follow a straight path or to follow a curved path the steering apparatus will ordinarily remain as set until manually changed. When the toy is built in the larger sizes a child can ride thereon and manipulate the steering wheel.

Having thus described the invention, what is claimed as new is—

1. In a toy motor vehicle, a front axle 60 comprising a wooden axle bar having a slot extending horizontally in each of its two opposite ends, two wooden stub axle bodies having each a relatively thin pivot ear on one end and a socket bored horizontally in 125 the opposite end thereof, the latter end be-

ing squared, the ears being arranged in said slots respectively and pivoted to the axle bar, and wooden axle journals secured in said sockets respectively and having each a collar integral therewith. 70

2. In a toy motor vehicle, the combination of a frame, a plurality of wooden axle members to support the frame, each axle member having a squared end and a prepared cylindrical socket therein, a plurality of wooden 75 wheels having an axle bore therein, and a plurality of wooden axle journals extending through the axle bore of the wheels respectively and into the socket of the axle members respectively and non-removably secured 80 therein, each of said journals having a collar integral therewith at the outside of the adjacent wheel.

3. In a toy motor vehicle, the combination with a rear axle, and wheels on the axle, of 85 an axle bar composed of wood and approximately square in cross-section, wooden stub axles pivoted to said bar, wheels on the stub axles respectively, two frame bars secured directly to the top of the axle bar and to 90 the top of the rear axle, a filling piece that is square in cross-section secured directly to the top of said bar, the filling piece extending to said frame bars, a floor board secured upon the frame bars and said filling 95 piece, two solid wooden blocks spaced apart upon said board and secured thereto and adapted to imitate an engine casing and a seat respectively, and a steering shaft rotatively guided by the solid block that is in 100 imitation of said casing.

4. In a toy motor vehicle, the combination with a rear axle, and wheels on the axle, of 105 a wooden axle bar, two frame bars secured to the axle bar and the rear axle, two wooden stub axles pivoted to the axle bar, wheels on the stub axles respectively, a floor board secured upon the frame bars and having an aperture therein adjacent to the axle bar, a 110 solid wooden block secured upon the floor board and having a guide bore therein extending to said aperture, a dash board secured to said block and having a guide hole therein aligning with said bore, a shaft extending through and guided in said bore 115 and said aperture and also in said hole, a tube loosely embracing said shaft and seated on said dash board, said tube extending nearly to the top of said shaft, a wheel secured to said shaft and supported upon said tube to support said shaft, a crank arm on 120 said shaft, and connections between said arm and said stub axles.

5. A toy motor vehicle comprising in combination an axle bar, a rear axle, two frame 125 bars secured to the top of the axle bar and extending divergently each from the other to the rear axle and secured directly thereto, a filling piece secured to the axle bar between said frame bars, wheels rotatable on 130

the rear axle, stub axles pivoted to the axle bar, wheels rotatable on the stub axles respectively, a floor board secured upon the frame bars and the filling piece and having an aperture therein, a block formed to imitate an engine hood and secured upon said board, said block having a guide bore there-in extending from said aperture, a dash board secured to said block and having a 10 guide hole therein alining with the upper end of said bore, a steering shaft guided in said bore by said block and also in said aperture and said hole, steering connections be-

15
20

tween said shaft and one of said stub axles, a coupler connected with said stub axles, a seat composed of a solid block secured upon said floor board, a body behind said seat supported on said frame bars, and imitation lamps on the forward portions of said frame bars.

In testimony whereof I affix my signature in presence of two witnesses.

WALTER O. McDANIEL.
